UNITED STATES PATENT OFFICE.

WILLIAM A. OLSEN, OF NEW YORK, N. Y.

SAFETY-LOCK FOR PINS.

No. 904,356.

Specification of Letters Patent. Patented Nov. 17, 1908.

Application filed July 31, 1907. Serial No. 386,453.

To all whom it may concern:

Be it known that I, WILLIAM A. OLSEN, a citizen of the United States, residing at New York, in the county of New York and State of New York, have invented new and useful Improvements in Safety-Locks for Pins, of which the following is a specification.

This invention relates to pins or more particularly to safety devices for securing pins when once located and are adapted to be secured to the point of the pin in such a manner after the pin has been passed through the article it is to secure, that its accidental retraction is hardly possible as will be more fully described in the following specification, set forth in the claim and illustrated in the drawings where it will be seen that the same reference characters are used to distinguish the same parts in the several figures.

Figure 1 is a perspective view of a hat pin with the improved securing device on its point. Fig. 2 is an enlarged side view of Fig. 3 is a sectional view of the device on the point of the pin.

The device is particularly adaptable for use on the points of such a scarf pin, hat pin or such articles of value which are frequently in danger of slipping out of the article in which they are located and being lost and consists of a bead or head 5 which may correspond in size and shape with the head 6 of the pin 7. This head 5 has a hollow shank 8 the interior being of about the same diameter as the end of the pin and the inner end of the socket 9 may correspond with the point of the pin as shown. One

side 10 of the shank 8 is reduced and flattened and this flattened side has a resilient effect. An indentation or depression 11 is formed in this portion 10 of the shank and projects far enough inward to decrease the diameter or width of the socket at that point to a degree less than the diameter of the pin so that it forms an obstruction to the entrance of the pin yet the resilient action of the flattened side 10 allows it to yield and the pin to slide past. This action of placing the head on the pin requires some force but when located the resiliency of the side 10 and the friction of the indentation serve to retain it firmly and against the possibility of displacement and loss.

It is obvious that other modified details within the scope of the claim may be adopted without departing from the essential features above described.

What I claim as new and desire to secure by Letters Patent is:

The combination with a pin of a safety device comprising a tubular member having one side externally flattened and reduced sufficiently to produce a resilient side, said side being provided with a transverse indentation forming an interior projection to frictionally engage the pin when the point of the latter is inserted into the tubular member.

In testimony whereof, I affix my signature in presence of two witnesses.

WILLIAM A. OLSEN.
